CLAIM

The ornamental design for a two-door dispenser for paper napkins, as shown and described.

DESCRIPTION

FIG. 1 a top, front, right side perspective view of the two-door dispenser for paper napkins showing our new design, the rear and left sides being mirror images of the front and right sides respectively;

FIG. 2 is a top plan view thereof;

FIG. 3 is a right side elevational view thereof, the opposite side being a mirror image; and,

FIG. 4 is a bottom plan view thereof.
